UNITED STATES PATENT OFFICE.

FRANCIS J. FRENCH, OF MILES GROVE, PENNSYLVANIA, ASSIGNOR OF
ONE-HALF TO JOHN R. HOLLIDAY, OF SAME PLACE.

DESIGN FOR A COMB AND PENCIL HOLDER.

SPECIFICATION forming part of Design No. 33,573, dated November 20, 1900.

Application filed June 11, 1900, Serial No. 19,962. Term of patent 7 years.

To all whom it may concern:

Be it known that I, FRANCIS J. FRENCH, a citizen of the United States, residing at Miles Grove, in the county of Erie and State of Pennsylvania, have invented and produced a new and original Design for a Comb and Pencil Holder, of which the following is a specification, reference being had to the accompanying drawings, forming a part thereof.

Figure 1 is a perspective view of a comb and pencil holder, showing a new design. Fig. 2 is a plan view of the bottom.

As shown in the drawings, the leading or material feature of my design consists of a box portion *a*, having two open sides *b* and *c*, closed sides *d* and *e*, and top and bottom sides *f* and *g*. A plate *h* extends from the base of the side *e* and is curled upwardly and over. A second plate *i* extends from the top side *f* and at right angles to the extension *h*. This extension is turned upwardly at its point of

connection with the top and is bent over to lie parallel thereto and at a slight distance therefrom. The extension *i* is substantially triangular in shape, and the apex of the triangle is broadened and rounded to form a disk *k*, upon which is mounted a button *l*. A tab *n* is stamped from the bottom side *g* and is bent up into the interior of the box *a*, as shown in Fig. 2.

Having described my invention, what I claim as new, and desire to secure by Letters Patent, is—

The design for a comb and pencil holder as herein shown and described.

In testimony whereof I sign my name, in the presence of two subscribing witnesses, on this 28th day of May, 1900.

FRANCIS J. FRENCH.
